CLAIM

The ornamental design for a horizontal shed, as shown and described.

DESCRIPTION

FIG. 1 is a front perspective view of a horizontal shed embodying the design of my new invention;

FIG. 2 is a top view of the horizontal shed;

FIG. 3 is a front view of the horizontal shed;

FIG. 4 is a side view of the horizontal shed as seen from the left hand side thereof;

FIG. 5 is a side view of the horizontal shed as seen from the right hand side thereof;

FIG. 6 is a rear view of the horizontal shed;

FIG. 7 is a bottom view of the horizontal shed; and,

FIG. 8 is a front perspective view, similar to FIG. 1, with the top of the horizontal shed open.

The broken lines showing the bottom and interior of the horizontal shed are for illustrative purposes only, and form no part of the claimed design.
